UNITED STATES PATENT OFFICE.

LOUIS PAUER, OF CLEVELAND, OHIO.

RACING GAME.

Application filed April 8, 1925. Serial No. 21,536.

To all whom it may concern:

Be it known that I, LOUIS PAUER, a citizen of the United States, residing at Cleveland, in the county of Cuyahoga and State 5 of Ohio, have invented new and useful Improvements in Racing Games, of which the following is a specification.

This invention is a useful and new or improved racing game played for entertainment and instruction in demonstrating the value of jockeyship under conditions closely approaching actual horse-racing contests. While adaptable for imitating other racing contests this game meets a combination suited particularly for the simulating of auto and horse-racing.

For the reproduction of auto racing by means of this invention the most important factor of speed with accidents and mishaps resulting therefrom is imitated through the introduction of a chance controlling element, a standard deck of playing cards being used in combination with a racing board and movable members under regulations providing for a series of drawings in which the drawing of certain high cards of predetermined values will enable a player to progress at a higher rate of speed while at the same time exposing him to loss of ground, if not elimination from the race, upon drawing more high cards in succession, in which event the player will be supposed to have suffered some natural consequence attending excessive speed, as a wreck 30 that may cause his elimination, or a hot-box, tire trouble and other mishaps that may only retard his progress. In order that the element of chance may not be the sole controlling factor and to enable the participants 35 to exercise their judgment in some degree, it is further provided that a player, upon drawing certain high cards, may elect to waive a part of the allowance to avoid loss of ground should he draw more high cards 40 in succession.

The most important factor in horse-racing when the starters are well matched is the strategy of the jockeys in avoiding interference or loss of ground from going wide 45 and their judgment in setting and forcing the pace or in saving their mounts for the final drive.

In the reproduction of horse-racing contests by means of this invention the most 50 important controlling factor is the skill or

judgment of the jockey-players, without the use of cards or the introduction of other chance elements over which a player may have no control, excepting as his chances in a race may be affected by the moves of the other players under regulations that will permit of a great variety of combinations of plays, and under different sets of rules that may be based substantially upon the main features employed in the construction 60 of the racing-board illustrated in the preferred embodiment of my invention, said rules being devised with a view of equalizing the winning chances of each player, skill and judgment otherwise equal, regardless of his post position at the start of a race.

In order to carry out these aims my invention provides playing periods that, under different sets of rules, may represent equal 75 or unequal distances of a race course. Within these playing periods are a series of rails or tracks intersected at regular intervals by distinguishable transverse lines or spaces, preferably numbered perforations, each representing a short distance comparable with the length of a horse.

Among other preferred regulations, a player may lose one or more lengths by exceeding a variable speed limit provided for 80 the different rails, or by traveling too slow, also by going wide around the turns and by crossing more than a limited number of rails in a single playing period to gain a 85 more advantageous position.

In order to offset the disadvantage of the starters in the outer rails at the turns, and to enable them to gain ground in the straightaway portions of the track, it is provided that the speed limit in the inner rails 90 shall be slightly less than that in the outer rails, on the assumption that horses cannot fully extend themselves in the inner positions where they may be forced to race in close quarters. This variation in the speed 95 limit for the different rails also imitates a track condition that often exists in actual racing when the footing near the inner rail is less firm which enables those on the outside to travel faster.

Now with reference to the drawings, Fig. 1 is a plan view of a board or base representing a race course designated as the racing-board. Fig. 2 is that of a movable member representing a jockey mounted on 100

105

110

a running horse, and Fig. 3 represents a racing auto. Fig. 4 represents movable tallying pegs.

Fig. 1 illustrates the preferred embodiment of a racing board to further the objects of my invention. For the base I prefer a wooden board, and I also prefer to fasten upon the upper surface of said board a thin layer of sheet metal provided with 10 slots as a retaining means for the movable members.

For the simulating of horse-racing Fig. 1 represents a mile course divided into eight playing periods, each representing equal distances corresponding with the fractional mile posts of a race course divided into eight furlongs. Under varying sets of rules the racing-board may however be divided into 20 any number of playing periods to represent equal or unequal distances. The playing periods are indicated by the word "period" printed or stamped upon the racing-board at the beginning or end of such periods and they are numbered in consecutive order to 25 indicate the distances and the direction in which the players move.

Within the playing periods and lines IR and OR, the same representing the inner and outer rails of a race course, are shown longitudinal slots in a series of broken lines parallel in the stretches and concentric about the turns. Said broken lines indicate rails or tracks, which in the preferred embodiment of my invention are eight in number, but on racing-boards of larger or smaller dimensions the number of rails may be increased or reduced. The numerals 1 to 8 inclusive printed or stamped upon the racing-board 40 from the inner to the outer rail of the course indicate the number of each rail.

The intervals shown by the broken lines are designated as playing positions, and they represent a distance comparable with the length of a starter, which may vary under 45 different sets of rules. Under my preferred regulations each interval represents one length of a horse. The number of said intervals in each playing period and in each rail is twelve, and they are numbered in 50 consecutive order by the numerals 75 to 86 inclusive to indicate the relative position of the players in the course of a race, it being assumed that the number of lengths in each 55 period is eighty, but that twelve playing positions will suffice to carry out the objects of this invention while economizing space. The number of these playing positions in each period may however be increased or reduced, and the number may vary in different 60 periods for various sets of rules.

Instead of the broken lines, as shown in Fig. 1, the rails with the playing positions may be delineated upon the racing-board by a series of lines intersected by transverse lines, circles or squares of varying colors to

guide the players in placing their figures which may be mounted on suitable supports. But with a view of preventing displacement of the figures I prefer to provide the racing-board with means for holding the figures in 70 position, and in order to insure the proper alignment of the figures and to protect the wearing surfaces of the retaining means, longitudinal slots are stamped into a thin layer of sheet metal which may consist of 75 one or more strips fastened upon the surface of the board. The movable members as shown in the drawing, Figs. 2 and 3, are provided with projections to engage in the 80 slots. The tallying pegs shown in Fig. 4 are 85 likewise provided with projections that engage in the rectangular slots of the tabulators, one at each end of the inner elliptical portion of the racing-board, for both horse and auto-racing used in tallying the number 90 of lengths lost and the distances traveled. When the autos have traveled ten miles an additional set of pegs is used to tally from ten to fifty miles after each block of ten miles. For ready reference the principal 95 playing rules are printed or stamped upon the inner portion of the racing-board.

The game of horse-racing is simulated by means of this invention under the following preferred regulations:—Each player is allowed the same total of lengths, the total number of lengths depending upon the distance of a race agreed upon, eighty lengths being allowed for each eighth of a mile. The jockeyed-players advance their figures 100 from one playing period to another within fixed and optional limits of travel that represent variations of one or more lengths of a horse, the players occupying the outer rails being permitted to travel relatively faster 105 while subjected to the loss of one or more lengths when going wide at the turns. All the players are further subjected to the loss of one or more lengths in single playing periods when they exceed the maximum and 110 travel below the minimum speed limits provided for the rails they occupy or enter, also when they cross more than a limited number of rails within a single period by 115 entering the inner rails to avoid loss of ground at the turns or to travel faster in the outer rails.

The players in starting these contests first draw for post positions by drawing numbers corresponding with the number of the figure they shall advance and the number of the rail they shall occupy at the start of the race. The player drawing number 1 then advances the figure of the same number and from the rail of that number into 120 the next playing period to any rail and playing position that in his judgment may seem most advantageous as he may try to anticipate the moves of the others who follow in 125 the order of their post positions.

The game once started, the player in the lead always moves first and the others follow in the order of their positions in the course of a race.

5 Players occupying or entering rails 1 and 2 may advance their figures from seventy-seven to eighty lengths in each playing period.

In rails 3, 4 and 5 the players may advance 10 their mounts from seventy-seven to eighty-one lengths, the maximum distance for a single period being equivalent to one furlong and one length. In two playing periods the maximum distance will equal two furlongs 15 and two lengths when a player occupying said rails may set his figure into playing position No. 82. Players remaining in rails 3, 4 and 5, or forced to enter the same in periods 2 and 6 will lose one length going 20 wide.

Players occupying rails 6, 7 and 8, or entering the same from other rails, may advance their mounts from seventy-seven to eighty-two lengths. Those remaining in 25 said rails or forced to enter the same in periods 1, 3, 5 and 7, partly on the turns, will lose one length going wide, and in periods 2 and 6 they will lose two lengths.

In any rail a player may advance his 30 mount one length in excess of the speed limit of the rail occupied or entered from another rail, at the cost of one length, and he will lose one length for each length traveled below the minimum speed limit of 35 seventy-seven lengths. Crossing more than three rails within a single period will result in a loss of one length for each rail crossed in excess of that number.

A player must remain at least two lengths 40 behind in following another starter occupying the same rail.

In order to enter or cross a rail in front of a starter occupying another rail one length behind, a player must advance his 45 mount at least eighty-one lengths in the next period, and with a lead of two lengths over the other starter he must travel at least eighty lengths in the next period to do so; when running abreast with another starter 50 a player must travel at least eighty-two lengths, it being assumed that all the starters will travel eighty lengths in each period whether or not they elect to do so.

When two or more players at the end of 55 a race finish in the same position in different rails, the winners are decided in the order of the rails they occupy, it being supposed that the contenders in that situation finish heads and noses apart.

60 When two or more players occupy the same playing positions in different rails, those in the inner rails move first, excepting when the players in the outer rails may travel faster without a loss by remaining in 65 or entering the outer rails. Thus, if three

players in period No. 3 should occupy the same playing positions in rails 2, 5 and 6, the player in rail 6 would advance his figure first and the player occupying rail 5 would follow. But with the same alignment in 70 period 4 the player occupying rail 5 will advance his figure first followed by the player in rail 2, the starter in rail 6 being forced to enter an inner rail to avoid loss of ground in period 5. With the same alignment in period 5 the player in rail 2 will advance his figure first, he being in the most advantageous position to avoid loss of ground in period 6, and the player occupying rail 5 will follow. 75 80

In order that a player may enter or cross a rail between two others occupying the same or adjacent rails, the other players must be separated by at least four lengths. Thus, if players 2 and 3 in period 5 should 85 occupy rail 2, separated by three lengths, or if player 3 should occupy rail 3 the same distance behind player 2 in rail 2, then the players in the outer rails could not enter or cross rail 2 between players 2 and 3 to avoid loss of ground in period 6. And if players 4 and 5 in period 3 should occupy rail 3, separated by three lengths, then the starters in rails 1 and 2 could not enter or cross rail 3 90 between players 4 and 5 to travel faster in 95 the outer rails.

When one of two players occupying adjacent rails must advance his figure first in the order of precedence, he may enter the adjacent rail so occupied, or he may cross the same, by allowing the other player to travel in his turn a distance of eighty lengths. Thus, if player 8 in period 4 should occupy rail 6, one length in advance of 100 player 7 in rail 5, then player 8, in order to avoid loss of ground from going wide in period 5, and being prevented from entering R5 in advance of P7, may enter or cross rail 5 by advancing his figure seventy-seven 105 lengths which will enable player 7 in his turn to travel eighty lengths.

When a player from an inner rail crosses an outer rail occupied by another traveling at a slow rate of speed, he may suffer a loss of ground from traveling below the speed limit. Thus, if player 5 in period 6 should occupy rail 3 and advance his figure only seventy-seven lengths into period 7, another player in crossing rail 3 from an inner rail would be forced to follow two lengths behind, which would entail a loss of two lengths from a position on even terms with player 5 in period 6 and a loss of one length from a position one length behind player 5 in the same period; but a player occupying a position two lengths behind player 5 in period 6 could cross rail 3 without a loss, and then, if he elects to do so, he may travel the maximum distance in another 115 120 125 rail. 130

In the absence of an agreement a race will be at one mile. It will be found that races of shorter and longer distances present different problems, but the same rules apply for all distances.

The number of lengths that each player has in reserve for the final playing period may be found readily by reference to the position he occupies and the number of lengths lost, if any. There is no need of taking into account the total number of lengths in a race. With a loss of one length a player can advance no farther at the finish than position No. 79, and to position No. 78 with a loss of two lengths. Thus, if player 1 in rail 1 and in period 7 were leading in position 85, without a loss charged against him, he would have seventy-five lengths left in reserve, with the result that in a race 20 at a mile he would lose two lengths in the final period, one for each length traveled less than seventy-seven, and he would finish in position No. 78. If player No. 2 were second in the race at that stage, in rail 2 and position No. 83, without a loss charged against him, he would have seventy-seven lengths in reserve which would enable him to win the race by finishing in position No. 80.

A player may win a race by gaining a position other than No. 80 if the others fail to pass him, when one or more starters, with enough lengths in reserve that would otherwise enable them to gain a more advanced position, may be blocked and forced to go wide around the turns or to cross more than three rails. The game presents innumerable combinations of plays as each player will be forced to follow different methods, depending upon his post position and as the alignment of the starters may force him to vary his tactics in each playing period.

By following various combinations a player may succeed in winning a race without a loss, and he may also win after losing one, two or three lengths, as he may sacrifice one or more lengths in gaining an advanced position when he may succeed in forcing the other players to lose ground, particularly with the co-operation of one or two players who have likewise made sacrifices when, in order to improve their winning chances, these players will be forced to co-operate in bringing about the defeat of the others who may try to win without suffering the same loss of ground. This strategy may be followed more consistently when each player advances two or more starters as his entries.

Any number of players may participate, not exceeding eight. And as a single player may experiment with various combinations by advancing all the starters, this invention also offers an interesting game of solitaire. In order that the position of the starters in each of the playing periods may remain

in view for the detection of irregularities and as a guide for the players in observing the moves of the other contestants, each player is provided with eight figures, one for each playing period. One set of pegs is used for tallying the number of lengths lost.

In simulating auto racing by means of this invention under my preferred regulations, the playing periods serve another purpose in that the drawing of different cards determines the number of periods a player will be allowed to advance his figure, each period representing one quarter of a mile, it being assumed that the racing-board represents a two-mile course. The playing positions in the rails also serve another purpose in that each indicates the denomination of the card last drawn by a player occupying the same, as for instance when a player draws an ace, which he may accept regardless of consequences should he draw another ace or other high card, he will advance his figure two and three-quarter miles and place it into the position designated by 1-A, the same being position No. 86 for horse-racing. And when a player draws a nine he will advance his figure one and three-quarter miles and place it into the position designated by 8-10, the same being position No. 77 for horse-racing.

For auto-racing the numerical order of the rails serves only to indicate the relative position of the driver-players in the course of a race. Thus, if player 6 were in the lead he would place his figure in position along rail No. 1, and if player 3 were second in the race he would place his figure along rail No. 2, but if 6 and 3 were passed by another they would then place their figures in rails Nos. 2 and 3 respectively. This will serve to show at a glance the order for the drawing of cards, the leader in a race always drawing the first card while the others follow in the order of their position in the course of a race. It is possible however for a player in last position to draw two cards in his turn if he should overhaul all the others in a single play.

Playing positions are provided for the drawing of a single ace, but not two aces, as this eliminates the player, it being supposed that his machine was wrecked as the result of traveling too fast. The drawing of an ace and then a king, or a king first followed by an ace, will greatly retard a player's progress in that he will be forced to remain at a stand-still while the others gain upon him or increase their lead, in which event it will be supposed that the delay was caused by a hot-box. The drawing of an ace followed by a queen or the same followed by an ace will retard a player's progress in that he will be permitted to advance his figure only one-quarter of a mile. The same distance is allowed upon the drawing of two

5 kings in successive drawings. The drawing of a king and then a queen, or in the reverse order, will advance a player only one-half mile, and the drawing of two queens three-fourths of a mile. Upon the drawing of one or more jacks the player will be permitted to advance his figure two miles for each.

10 The playing positions provided for the drawing of jacks and other cards of lower denominations serve only as a convenience in placing the figures and to control the order of precedence in drawing cards.

15 A player drawing a high card may waive part of the allowance when he will place his figure into the position provided for the allowance he accepts, as if he had drawn a card of a lower denomination.

20 Instead of the broken lines, as shown in Fig. 1, the rails with the playing positions may be delineated upon the racing-board by a series of lines intersected by transverse lines, circles or squares of varying colors to guide the players in placing their figures which 25 may be mounted on suitable supports. But with a view of preventing displacement of the figures I prefer to provide the racing-board with means for holding the figures in position, and in order to insure the proper 30 alignment of the figures and to protect the wearing surfaces of the retaining means, longitudinal slots are stamped into a thin layer of sheet metal which may consist of one or more strips fastened upon the upper 35 surface of the board. The movable members as shown in the drawing, Figs. 2 and 3, are provided with projections to engage in the slots. The tallying pegs shown in Fig. 4 are likewise provided with projections that engage in the rectangular slots of the tabulators, one at each end of the inner elliptical 40 portion of the racing-board, for both horse and auto-racing that are used in tallying the number of lengths lost and the distances 45 traveled. When the autos have traveled ten miles an additional set of pegs is used to tally from ten to fifty miles after each block of ten miles. For ready reference the principal playing rules are printed or stamped 50 upon the inner portion of the racing-board.

Examples in horse and auto-racing.

55 The following is an example showing how eight players may advance their figures in a game simulating horse-racing at a distance of one mile, the abbreviations P, R, Po and L being used for Player, Rail, Position and Length respectively:—

60 Period 1. P1—R3—Po 82, loss one L exceeding speed limit of 81 Ls in R3; P2—R2—Po 80; P3—R1—Po 80; P4—R4—Po 81; P5—R5—Po 81; P6—R6—Po 82, loss one L going wide in R6; P7—R5—Po 79; 65 P8—R5—Po 77.

In order to enter R3 where he can travel faster and to enable him to cross in front of players 2 and 3, P1 must travel 82 Ls, his object being to avoid interference by sacrificing one or more Ls in gaining a forward 70 position that will enable him to force others to lose ground in the course of the race. Under favorable developments, with five or six players taking losses in the early stages of a race, a player might win by sacrificing 75 one or more Ls, but in this example the winning chances of P1 are lessened when players 2, 3, 7 and 8 advance their figures with a view of avoiding losses at the first 80 turn.

Period 2. P1—R3—Po 83, loss one L going wide in R3, total loss two Ls; P6—R4—Po 83, loss one L going wide in R4, total loss two Ls; P4—R4—Po 81, loss one L going wide in R4; P5—R5—Po 82, loss one L going wide in R5; P3—R1—Po 80; P2—R2—Po 80; P7—R2—Po 78; P8—R2—Po 76. In this period players 7 and 8 cross three rails to avoid loss of ground by entering R2. 90 With a lead of one L in period 1, P6 is enabled to cross in front of players 4 and 5 by traveling 81 Ls in entering R4.

Period 3. P1—R3—Po 84; P6—R4—Po 84; P5—R5—Po 83; P4—R4—Po 82; P2—R5—Po 81; P3—R3—Po 81; P7—R3—Po 95 78; P9—R4—Po 77. While the players in this period save ground by avoiding rails 6, 7 and 8, they also avoid rails 1 and 2 to travel faster in rails 3, 4 and 5.

Period 4. P6—R4—Po 85; P1—R3—Po 100 85; P5—R6—Po 85; P4—R4—Po 83; P2—R6—Po 83; P3—R3—Po 82; P7—R3—Po 79; P8—R4—Po 78. Both occupying Po 84 in period 3, P6 is entitled to precedence over P1 in the order of their moves, P6 being 105 in a position to enter R6 where he could travel faster without a loss if he elected to do so. For the same reason P2 is entitled to precedence over P3 in this period, each occupying Po 81 in period 3.

Period 5. P1—R1—Po 85; P6—R2—Po 84; P5—R3—Po 83; P4—R4—Po 83; P2—R5—Po 83; P3—R2—Po 82; P7—R3—Po 80; P8—R4—Po 79. In period 4 players 1, 6 and 5 occupy the same playing positions in rails 3, 4 and 6 respectively, but as P1 is in the most favorable position he moves first in entering period 5. At this stage P5 has lost only one L, but with players 1 and 6 occupying rails 1 and 2 he will be forced to lose another length going wide in period 6, which will prevent him from heading players 1 and 6. As it would be useless for him to continue forcing the pace, P5 now begins to travel slower with a view of crowding back those behind him, and having a two-length lead over P4, P5 is in a position to cross three rails to enter R3—Po 83, just far enough to prevent the others from passing him in the next period. In order to 110 120 125 130

6
avoid a loss from going wide in period 5—R6, P2 enters R5.

Period 6. P1—R1—Po 84; P6—R2—Po 83; P5—R3—Po 82, loss one L going wide in R3, total loss two Ls; P4—R4—Po 81, loss one L going wide in R4, total loss two Ls; P2—R5—Po 80, loss one L going wide in R5; P3—R2—Po 79; P7—R2—Po 77; P8—R4—Po 79, loss one L going wide in R4. In period 6 P1 travels 79 Ls to prevent P6 from gaining a two-length lead over him. With a view of preventing the trailers from gaining ground, P4 travels 78 Ls, and P2 only 77. As P3 cannot expect to get through in one of the inner rails, he must try for the outside and falls back advancing only 77 Ls in R2, which also crowds back P7 who follows in the same rail. P8 now takes his first loss by going wide in R4—Po 79 with a view of going around the leaders. At this stage 3 and 7 are the only players without a loss.

Period 7. P1—R1—Po 81; P6—R2—Po 81; P5—R3—Po 80; P4—R4—Po 78; P2—R5—Po 78; P8—R5—Po 80; P3—R5—Po 76; P7—R4—Po 76. In period 7 players 1 and 6 advance their figures into Po 81, which leaves them 77 Ls in reserve to finish in Po 78; each having lost two Ls; they can advance no farther. P4 travels only 77 Ls advancing into Po 78 to crowd back those behind him who might enter R4. P2 in R5 does likewise traveling only 78 Ls, but he overlooks P8 who may now pass around him. From Po 79—R4, P8 is enabled to pass P2 and to enter R5—Po 80, two Ls in advance of P2, thereby traveling 81 Ls in R5 while crossing not more than three rails, two rails from 4 into 6 and one rail from 6 back into R5; by entering R5 in period 7, P8 also avoids a loss going wide in R6. In period 7, P3 is forced to enter R5—Po 76; he cannot enter R6 because that would entail a loss of two Ls, one for crossing four rails from R2 into R6, and the other from going wide in R6. This also forces P7 into the same position in R4.

Finish. P6—R2—Po 78, total loss two Ls; P1—R1—Po 78, total loss two Ls; P8—R5—Po 79; total loss one L; P5—R3—Po 78, total loss two Ls; P2—R6—Po 79, total loss one L; P4—R4—Po 78, total loss two Ls; P3—R7—Po 79, loss one L exceeding speed limit in R7, total loss one L; P7—R8—Po 78, loss one L crossing four rails, total loss one L. The race is won by P8 with P2 finishing a close second and P3 a close third.

60 The following is an example showing how eight players may advance their figures in a game simulating auto-racing at a distance of twenty miles:

First draw. P1 draws a four, dis $1\frac{1}{4}$ Ms, advancing into period 5—R1—Po 2—4. P2 also draws a four, dis $1\frac{1}{4}$ Ms, into period

5—R2—Po 2—4. P3 draws an ace which he accepts for the full distance, $2\frac{3}{4}$ Ms, into period 3—R1—Po 1—A, tallying two Ms; P1 now entering R2 and P2—R3. P4 draws an eight, dis $1\frac{3}{4}$ Ms, into period 7—R2—Po 8—10; P1 now entering R3 and P2—R4. P5 draws a three, dis $1\frac{1}{4}$ Ms, into period 5—R5—Po 2—4. P6 draws an ace which he accepts for the full distance, $2\frac{3}{4}$ Ms, advancing into period 3—R2—Po 1—A, tallying two Ms; P4 now entering R3, P1—R4, P2—R5 and P5—R6. P7 draws a seven, dis $1\frac{1}{2}$ Ms, into period 6, R4—Po 5—7; P1 now entering R5, P2—R6 and P5—R7. P8 draws a six, dis $1\frac{1}{2}$ Ms, into period 6—R5—Po 5—7; P1 now entering R6, P2—R7 and P5—R8. The cards are now shuffled for the next draw.

Second draw. P3 occupying R1 draws a deuce, dis $1\frac{1}{4}$ Ms, advancing from period 3 into 8—R1—Po 2—4, tallying two Ms for a total of four Ms. P6 is lucky in drawing a ten after an ace, dis $1\frac{3}{4}$ Ms, from period 3 into 2—R1—Po 8—10, tallying two Ms for a total of four Ms; P3 now entering R2, P4 draws a deuce, dis $1\frac{1}{4}$ Ms, from period 7 into 4—R3—Po 2—4, tallying two Ms. P7 draws a jack, dis 2 Ms, advancing from period 6 into the same period, R3—Po JA, tallying two Ms; P4 now entering R4—Po 4—95. P8 draws a three, dis $1\frac{1}{4}$ Ms, from period 6 into 3—R5—Po 2—4, tallying two Ms. P1 draws a king which he accepts for the full distance of $2\frac{1}{2}$ Ms, advancing from period 5 into 7—R3—Po 1—K, tallying two Ms; P7 now entering R4, P4—R5 and P8—R6. P2 draws a seven, dis $1\frac{1}{2}$ Ms, from period 5 into 3—R6—Po 5—7, tallying two Ms; P8 now enters R7, one L behind P2. P5 draws a ten, dis $1\frac{3}{4}$ Ms, from period 5 into 4—R5—Po 8—10, tallying two Ms; P4 now entering R6, P2—R7 and P8—R8. The cards are shuffled after each draw.

Third draw. P6 draws and accepts an ace for the full distance, $2\frac{3}{4}$ Ms, advancing from period 2 into 5—R1—Po 1—A, tallying two Ms for a total of six Ms. P3 draws a three, dis $1\frac{1}{4}$ Ms, from period 8 into 5—R2—Po 2—4. P1 draws a four, dis $1\frac{1}{4}$ Ms, from period 7 into 4—R3—Po 2—4, tallying two Ms for a total of four Ms. P7 draws an eight, dis $1\frac{3}{4}$ Ms, from period 6 into 5—R3—Po 8—10, tallying two Ms for a total of four Ms; P1 now entering R4. P5 draws a nine, dis $1\frac{3}{4}$ Ms, from period 4 into 3—R5—Po 8—10, tallying two Ms for a total of four Ms. P4 draws a seven, dis $1\frac{1}{2}$ Ms, from period 4 into 2—R6—Po 5—7, tallying two Ms for a total of four Ms. P2 draws a ten, dis $1\frac{3}{4}$ Ms, from period 3 into 2—R6—Po 8—10, tallying two Ms for a total of four Ms; P4 now entering R7. P8 draws a six, dis $1\frac{1}{2}$ Ms, from period 3 into 1—R8—Po 5—7, tallying two Ms for a total of four Ms.

Fourth draw. P6 is lucky for the second time in drawing a jack after an ace, dis 2 Ms, advancing from period 5 into the same period, R1—Po JA, tallying two Ms for a total of eight Ms. P3 draws a six, dis $1\frac{1}{2}$ Ms, from period 5 into 3—R2—Po 5—7, tallying two Ms for a total of six Ms. P7 draws and accepts a queen, dis $2\frac{1}{4}$ Ms, from period 5 into 6—R2—Po 1—Q, tallying two Ms for a total of six Ms; P3 now entering R3. P1 draws a duce, dis $1\frac{1}{4}$ Ms, from period 4 into 1—R4—Po 2—4, tallying two Ms for a total of six Ms. P5 draws a five, dis $1\frac{1}{2}$ Ms, from period 3 into 1—R4—Po 5—7, tallying two Ms for a total of six Ms; P1 now entering R5. P2 draws a four, dis $1\frac{1}{4}$ Ms, from period 2 into 7—R6—Po 2—4. P4 draws a three, dis $1\frac{1}{4}$ Ms, from period 1 into 7—R7—Po 2—4. P8 draws an eight, 2 into 8—R6—Po 8—10, tallying two Ms for a total of six Ms; P2 now entering R7 and P4—R8. P6 draws a five, dis $1\frac{1}{2}$ Ms, from period 5 into 3—R1—Po 5—7, tallying two Ms for a total of ten Ms. P7 draws and accepts an ace, dis $2\frac{3}{4}$ Ms, from period 6 into 1—R2—Po 1—A, tallying four Ms for a total of ten Ms. P3 draws a five, dis $1\frac{1}{2}$ Ms, from period 3 into 1—R3—Po 5—7, tallying two Ms for a total of eight Ms. P5 draws a five, dis $1\frac{1}{2}$ Ms, from period 1 into 7—R4—Po 5—7. P1 draws a four, dis $1\frac{1}{4}$ Ms, from period 1 into 6—R5—Po 2—4. P8 draws a three, dis $1\frac{1}{4}$ Ms, from period 8 into 5—R6—Po 2—4. P2 draws an eight, dis $1\frac{3}{4}$ Ms, from period 7 into 6—R5—Po 8—10, tallying two Ms for a total of six Ms; P1 now entering R6 and P8—R7. P4 draws a seven, dis $1\frac{1}{2}$ Ms, from period 7 into 5—R8—Po 5—7, tallying two Ms for a total of six Ms. Sixth draw. P6 draws a nine, dis $1\frac{3}{4}$ Ms, from period 3 into 2—R1—Po 8—10, tallying two Ms for a total of twelve Ms. P7 draws a six, dis $1\frac{1}{2}$ Ms, from period 1 into 7—R2—Po 5—7. P3 draws a ten, dis $1\frac{3}{4}$ Ms, from period 1 into 8—R3—Po 8—10, tallying two Ms for a total of ten Ms. P5 draws a six, dis $1\frac{1}{2}$ Ms, from period 7 into 5—R4—Po 5—7, tallying two Ms for a total of eight Ms. P2 draws two Ms for a total of eight Ms, and accepts a queen, dis $2\frac{1}{4}$ Ms, from period 6 into 7—R4—Po 1—Q, tallying two Ms for a total of eight Ms; P5 now entering R5. P1 draws and accepts a king, dis $2\frac{1}{2}$ Ms, from period 6 into 8—R3—Po 1—K, tallying four Ms for a total of ten Ms; P3 now entering R4, P2—R5 and P5—R6. P8 draws and accepts a queen for a distance of $2\frac{1}{4}$ Ms, and accepts a queen for a distance of $2\frac{1}{4}$ Ms, from period 5 into 6—R6—Po 1—Q, tallying two Ms for a total of eight Ms; P5 now entering R7. P4 draws a ten, dis $1\frac{3}{4}$ Ms, from period 5 into 4—R8—Po 8—10, tallying two Ms for a total of eight Ms. 65 Seventh draw. P6 draws a queen and accepts it as a jack, dis 2 Ms, from period 2 into the same, R1—Po JA, tallying two Ms for a total of fourteen Ms. P7 draws a six, dis $1\frac{1}{2}$ Ms, from period 7 into 5—R2—Po 5—7, tallying two Ms for a total of twelve Ms. P1 draws a queen after a king, advancing only $\frac{1}{2}$ M, from period 8 into 2—R3—Po K—Q. P3 draws and accepts a king, dis $2\frac{1}{2}$ Ms, from period 8 into 2—R3—Po 1—K, tallying two Ms for a total of twelve Ms; P1 now entering R4. P2 draws a three, dis $1\frac{1}{4}$ Ms, from period 7 into 4—R4—Po 2—4, tallying two Ms for a total of ten Ms; P1 now entering R5. P8 draws a nine, dis $1\frac{3}{4}$ Ms, from period 6 into 5—R4—Po 8—10, tallying two Ms for a total of ten Ms; P2 now entering R5 and P1—R7. P4 draws an eight, dis $1\frac{3}{4}$ Ms, from period 4 into 3—R7—Po 8—10, tallying two Ms for a total of ten Ms; P1 now entering R8. Eighth draw. P6 draws an eight, dis $1\frac{3}{4}$ Ms, from period 2 into 1—R1—Po 8—10, tallying two Ms for a total of sixteen Ms. P7 draws a jack, dis 2 Ms, from period 5 into the same, R2—Po JA, tallying two Ms for a total of fourteen Ms. P3 also draws a jack, dis 2 Ms, from period 2 into the same, R3—Po JA, tallying two Ms for a total of fourteen Ms. P8 draws a four, dis $1\frac{1}{4}$ Ms, from period 5 into 2—R4—Po 2—4, tallying two Ms for a total of twelve Ms. P5 draws a ten, dis $1\frac{3}{4}$ Ms, from period 4 into 3—R4—Po 8—10, tallying two Ms for a total of twelve Ms; P8 now entering R5. P2 draws and accepts an ace, dis $2\frac{3}{4}$ Ms, from period 4 into 7—R4—Po 1A, tallying two Ms for a total of twelve Ms; P5 now entering R5 and P8—R6. P4 draws a nine, dis $1\frac{3}{4}$ Ms, from period 3 into 2—R6—Po 8—10, tallying two Ms for a total of twelve Ms; P8 now entering R7. P1 draws a three, dis $1\frac{1}{4}$ Ms, from period 2 into 7—R8—Po 2—4. Ninth draw. P6 draws a queen and accepts it as a jack, dis 2 Ms, from period 1 into the same, R1—Po JA, tallying two Ms for a total of eighteen Ms. P7 draws a six, dis $1\frac{1}{2}$ Ms, from period 5 into 3—R2—Po 5—7, tallying two Ms for a total of sixteen Ms. P3 draws a queen after a king, advancing only $\frac{1}{2}$ M, from period 2 into 4—R3—Po K—Q. P2 draws a king after an ace and remains in the same period, P5 draws a nine, dis $1\frac{3}{4}$ Ms, from period 3 into 2—R4—Po 8—10, tallying two Ms for a total of fourteen Ms; P2 now entering R5. P4 draws and accepts a king, dis $2\frac{1}{2}$ Ms, from period 2 into 4—R3—Po 1—K, tallying two Ms for a total of fourteen Ms; P3 now entering R4, P5—R5 and P2—R6. P8 draws a seven, 130

dis $1\frac{1}{2}$ Ms, from period 2 into 8—R6—Po 5—7, tallying two Ms for a total of fourteen Ms; P2 now entering R7. P1 draws a ten, dis $1\frac{3}{4}$ Ms, from period 7 into 6—R7—Po 5 8—10, tallying two Ms for a total of twelve Ms; P2 now entering R8.

Tenth draw. P6 now draws an eight, dis $1\frac{3}{4}$ Ms, from period 1 into 8—R1—Po 8—10, tallying two Ms for a total of twenty Ms.

10 As the other players now have no chance in another draw to finish in advance of the leader in Po 8—10, P6 wins the race. This drawing may be completed and additional drawings may be had to decide the winners 15 of second, third and fourth positions.

Having thus described my invention what I claim as new and desire to secure by Letters Patent is:—

1. For a game simulating racing contests 20 upon a board or base in combination with movable figures representing starters, the contestants in the order of their standing in a race periodically advancing the same for a predetermined total of lengths depending 25 upon the distance of a race, each move representing an advance comparable with the distance between fractional mile posts of a race course and within fixed and optional limits of travel equaling one or more lengths 30 of the starters represented by the movable figures, the starters in the outer positions being permitted to travel relatively faster while subjected to the loss of one or more lengths in going wide around the turns, said 35 starters being further subjected to the loss of one or more lengths when exceeding maximum and traveling below minimum speed limits and when crossing more than a limited number of rails in gaining a more 40 advantageous position:—A diagram upon a board or base delineating one or more consecutively numbered playing periods, each representing a predetermined distance of travel corresponding with the distance between one or more fractional 45 mile posts of a race course, said playing periods comprising a series of numbered

50 a series of numbered parallel and concentric lines designated as rails, the same being subdivided at regular intervals by consecutively numbered transverse lines or perforations 55 constituting at the intersections a series of playing positions, each representing a predetermined distance comparable with the length of the starters, the playing positions occupied by the contestants indicating their 60 progress within fixed and optional limits of travel in each playing period, said playing positions representing only a limited number of lengths in such playing periods of a predetermined total for economizing space 65 upon the racing-board.

2. For a game simulating automobile racing upon a board or base in combination with a standard deck of playing cards of predetermined values and movable figures 70 representing autos, the contestants in the order of their standing in a race periodically advancing the same variable distances determined by the cards drawn, said cards of higher values when drawn in succession 75 simulating unfavorable occurrences attending excessive speed by retarding the progress of the players in the course of a race:—A diagram upon a board or base delineating one or more consecutively numbered playing 80 periods, each representing a predetermined distance of travel corresponding with the distance between one or more fractional mile posts of a race course, said playing periods comprising a series of numbered 85 parallel and concentric lines designated as rails, the same being subdivided at regular intervals by transverse lines or longitudinal perforations designated by letters and numerals as playing positions indicating the 90 denomination or the distance value of the card last drawn by the players occupying the same, the playing positions being occupied by the players in the rails corresponding in number with their standing in the course of a race.

LOUIS PAUER.
